US0D1111714S

(12) United States Design Patent (10) Patent No.: US D1,111,714 S
(45) Date of Patent: * Feb. 10, 2026

(54) MEAT CLAWS

(71) Applicant: Dansons US, LLC, Scottsdale, AZ (US)

(72) Inventor: Garrett Matz, Scottsdale, AZ (US)

(73) Assignee: Dansons US, LLC, Scottsdale, AZ (US)

() Term: 15 Years

(21) Appl. No.: 29/951,941

(22) Filed: Jul. 12, 2024

(51) LOC (15) Cl. 07-06

(52) U.S. Cl.

USPC D7/683

(58) Field of Classification Search
